DRIVING MECHANISM FOR MOTION
PICTURE PROJECTORSErnest S. Carpenter, Cleveland Heights, Ohio, as-
signor to The Augustus-Carpenter Company,
Cleveland, Ohio, a corporation of Ohio

Application August 5, 1933, Serial No. 683,737

22 Claims. (Cl. 88—17)

This invention is a continuation in part of my copending application Serial No. 511,250, filed January 26th, 1931, and relates to a motion picture projector having a motor and suitable gearing driven thereby for operating either reel to feed the film forward or backward, as well as to operate the intermittent feed, the shutter and a fan for cooling the lamp.

The object of my invention is to provide a selective unitary control device associated with effective operating mechanism so that, by different positions of such control, I may connect the motor and its driven mechanism for ordinary exhibiting, or for reversing, and by a simple movement energize the lamp and start the motor. The invention also provides a position for directly rewinding onto the original reel, and a position for projecting a still picture.

A further object is to provide driving connections which will, through a suitable unitary controller, enable the different driving connections to be made in any order desired, and without damage to the operating mechanism or to the film.

In accomplishing the above objects, I provide a unitary control, such as is described and claimed in my copending application heretofore referred to, and which comprises a rotary controller barrel having contacts on its periphery which coat with contacts in a suitable housing for the barrel, all arranged so that by turning the knob to a given position, all the contacts, except the main switch, are set for the operation to be performed. I arrange the main switch so that it is operated by longitudinal movement of the controller knob.

I further provide a novel arrangement of gearing, clutches and operating mechanism therefor which is responsive to the electrical circuits controlled by the switch member. Accordingly, by rotating the knob to a desired position and then moving it axially, the projecting machine may be caused to perform any selected one of its four operations of forward drive, reverse drive, rewind and still exhibit.

In the drawings, Fig. 1 is a side elevation of a motion picture apparatus embodying my invention; Fig. 2 is a horizontal section through the controller unit, as indicated by the line 2—2 on Fig. 1, being on a larger scale; Fig. 3 is a similar view of the controller unit, with some of the parts in different positions; Fig. 4 is a vertical section through the controller unit on a plane parallel with Fig. 1, as indicated by the line 4—4 on Fig. 2; Fig. 5 is a development of the outer periphery of the controller barrel; Fig. 6 is a diagrammatic vertical section on a plane parallel with Fig. 1,

illustrating the various motor-driven mechanisms; Figs. 7, 8, and 9 are sections, as indicated by the correspondingly numbered lines on Fig. 6; Fig. 10 is a detail section as indicated by the lines 10—10 on Fig. 1; Fig. 11 is a detail section and is 5 indicated by the lines 11—11 on Fig. 10. Figs. 12, 13, 14, and 15 are electrical diagrams showing the connection utilized for controlling the projection machine, with the heavy lines of each figure showing the current path during the forward, reverse, rewind and still positions of the machine, respectively.

As shown in Figs. 1 and 2, the frame of my projector comprises an upright hollow standard 10 mounted on a suitably extending base 11 and 15 carrying at its rear a support 12 for the lamp and lens and carrying on its forward side two diagonally projecting hollow brackets 13, 14, on which the reel-holding arms 15, 16 are mounted, preferably by hinge connections. 20

The motor, the operating mechanism for driving either reel and rotating the shutter and for giving the intermittent feed to the film, and a motor-driven fan for cooling the lamp, are all contained within the hollow standard 10. At the 25 side of the standard 10 and above the base 11 is an offset portion 18 of the hollow frame which carries the unitary control hereinafter described.

The mechanism for rotating one reel or the other and for driving the intermittent feed and 30 shutter are illustrated in Figs. 6 to 11, inclusive. In those views M indicates an electric motor, R indicates a resistance in series with one of the field terminals of the motor, r a line running directly to such field terminal by-passing the re- 35 sistance. The motor is indicated as having a shaft m carrying the fan f which serves to cool the lamp indicated at L. The motor, by suitable gearing to be described, drives each reel through ratchets, so that backward rotation of either reel drive is 40 idle. The motor also may actuate the intermittent feed I, i and the shutter H. S indicates a solenoid which is adapted to operate a clutch to throw out of action the intermittent feed and shutter and the forward drive. 45

With the parts as just described, and irrespec- 50 tive of the form of the other mechanisms, an energization of the motor in series with the resistance, and with the solenoid idle, will drive the intermittent feed and shutter and one reel or the other, according to the direction of rotation of the motor, to feed the film in either direction and give the intermediate portion the necessary intermittent feed for exhibition purposes. 55 The coupling of the motor in the reverse direc-

tion, but with the resistance out and the solenoid active, will effect the rapid rotation of the original reel without operating the intermittent feed or shutter to give an effective rewinding operation. Finally, a connection through the resistance to the motor for forward operation and through the solenoid to throw out the clutch, will disconnect the intermittent feed, the shutter, and the forward drive, leaving the motor to operate the fan to cool the lamp, so the parts are proper for a still projection of whatever view happens to register with the lens and lamp.

In order to enable the above operation to be better understood, I will describe the particular driving mechanism shown in Figs. 6 to 9 inclusive, and particularly the drive for the upper reel N of film which is driven to reverse the film or to rewind the film on the original reel N. As there indicated, I have rigidly mounted on the motor shaft m, adjacent its upper end, a spiral gear 120, which meshes with a spiral 121 pinned to a transversely extending horizontal shaft 122 mounted in suitable bearings 123 carried by the frame 10. Rigidly secured to this shaft 122 is a spiral gear 124, which meshes with a spiral 125 on a reel driving shaft 126. This shaft is connected by a clutch 127 with an extension 128, which carries a bevel gear 129 meshing with a bevel gear 130 carried by a rotary stud 16 which carries the original reel N of film.

The lower reel W of film is driven by the motor M through the shaft m to wind the film during normal or forward operation of the machine. As shown in Figs. 6 to 9 a spiral gear 133 is loosely secured to the motor shaft m and arranged to be selectively driven thereby through the medium of a jaw clutch, one member 134 of which is rigidly secured to the shaft m and the other member 135 of which is keyed for sliding movement on an extended hub 136 of the spiral 133 and normally urged into engagement with the clutch member 134 by a suitable compression spring 137. The spiral 133 meshes with a spiral gear 140, rigidly secured to a longitudinally extending horizontal shaft 141, to which is also rigidly secured the shutter H and a spiral 143. The spiral meshes with a smaller spiral 144 carried by a transverse shaft 145 to which is secured a second spiral 146 which meshes with a spiral 147 on a reel driving shaft 148. This shaft is connected by a clutch 149 with an extension 150, which carries a bevel gear 151 meshing with a bevel gear 152 carried by the rotary stud 15 which carries the reel W.

The two clutches 127 and 149, above referred to, each comprise separate members mounted on the respective driving and driven shafts and having coacting shoulders adapted to effectively engage when such driving member is rotated in the driving direction. Each of the driving shafts 126 and 148 is capable of a slight axial movement, and as such driving member is driven in each case by a spiral gear, there is a longitudinal thrust on this driving shaft according to its direction of rotation. When the rotation is in the driving direction the pressure of the spiral gear teeth forces the shaft and its clutch member axially into engagement with its mate. Whenever the direction of the spiral is reversed to operate the shaft in the idle direction, no slipping of the clutch takes place, because the thrust of the driving spiral acts in the opposite direction to withdraw the shaft to axially separate the clutch members, as shown in the case of the clutch 127, in Fig. 6. This peculiar separable driving mechanism is claimed per se in my copending appli-

cation which now is Patent 1,920,967 issued on August 8th, 1933.

The intermittent drive shown in Fig. 6 is along the lines of the drive shown in my Patent No. 1,920,969, issued August 8th, 1933, and reference is made to that patent for a fuller description. Briefly, as here shown in Fig. 6, there is a grooved cam wheel 1 rigid on the shaft 141. This wheel has a peripheral groove which for most part lies in a radial plane, but at its ends turns outwardly 10 diagonally in opposite directions. This groove cooperates with pins on a wheel i, carried by a transverse shaft 153, so as to turn that wheel one tooth for each rotation of the shaft P. The transverse shaft 153 projects outwardly through 15 the casing 16 and carries on its outer end a film engaging sprocket 154 provided with teeth 155 arranged to engage the film perforations. The shaft 153 is disposed so that the film engaging sprocket is substantially beneath and tangent 20 to the film guide 156 which guides the film in the path of the projector light. Hence, an intermittent movement is imparted to the film adjacent the projection point.

The intermittent movement is not relied upon 25 to draw the film from either reel N or W. Instead, a loop of film is always maintained between the two reels to prevent distortion of the projected pictures, due to the reaction of the driving pressure on the film. As shown, the film 30 is drawn from the upper reel by a driving sprocket 160 rigidly mounted on the outer end of a transverse shaft 161, which is journaled in suitable bearings carried by the frame 10. The shaft 161, together with the sprocket 160, are continuously 35 driven at a rate of speed sufficient to maintain the film in a free loop between the driving sprocket 160 and the guide 156. As shown in Figs. 6, 8, and 9, a spiral 162 is secured on the shaft 161 and meshes with a larger spiral gear 40 163, which is rigidly secured to the shutter shaft 141. The shaft 161 is driven from the motor M through the medium of the clutch 134, 135, heretofore described.

A loop of film is likewise maintained between 45 the lower reel W and the intermittent motion sprocket 154. As shown, there is a continuously moving sprocket 164 disposed in the path of the film between the sprocket 154 and the reel W. The sprocket 164 is rigidly secured to one end 50 of the shaft 145 heretofore described, and which is driven from the motor M through the medium of the clutch 134, 135 and the spiral gears 143 and 144.

The clutch 134 and 135 is operated by the solenoid S. As shown in Figs. 6 and 7, the clutch member 135 is provided with an annular recess, which is engaged by a pivoted yoke 166, which is rocked by the solenoid through a loosely pivoted arm 167. The spring 131, together with an auxiliary spring 167a retain the yoke and arm together with the clutch member 135 in their uppermost position, in which position the clutch member 135 is in engagement with the clutch member 134 and a driving connection is established between the shaft m and the shaft 141. However, when electrical energy is supplied to the solenoid, the clutch member 135 is drawn downward out of connection with the clutch member 134 and the driving connection between the shafts m and 141 is broken. When, however, the solenoid is active, the pivoted yoke 166 withdraws the clutch and thereby renders inactive the shutter, the intermittent feed and the advance reel W.

When the solenoid is idle, if the motor is operated in the direction to turn the driving reel W in the direction of the arrow, Fig. 6, the clutch 134, 135 operates to complete the driving connection between the shafts *m* and 141, and the clutch 127 rotates idly, with the result that the film is progressed from the reel N to the reel W, intermittently operated by the wheel *i* and intermittently exposed by the shutter H, this being known as the forward drive of the machine. When the motor operates the drive of the reel N in the winding direction, the clutch 149 for the other reel is idle, this gives the reverse.

In rewinding, the direction of movement is the same as reverse, but the motor is speeded up by cutting out the resistance, which cuts in the solenoid, and as the film then passes directly from the reel W to the reel N, the intermittent movement and shutter, which are driven from the shaft 141 are idle, due to the action of the solenoid in breaking the driving connection between the shafts *m* and 141. For the still operation, the energization of the solenoid disconnects the intermittent feed and the shutter and the forward drive to the reel W, while the direction of the rotation of the motor is such that the clutch J is moved in the idle direction and hence the reel N is not moved. The motor therefore accomplishes only the cooling of the lamp. The intermittent movement may be then manually operated by turning a knob 170 on the forward end of the shaft 141 to bring any particular view desired into registration with the lamp.

The studs 15 and 16 which carry and rotate the reels W and N respectively are both normally driven through a frictional engagement with their respective driving gears 152 and 130. This driving arrangement prevents damage to the film due to the fact that the peripheral speed of the roll of film fluctuates as the film is wound and unwound. I find, however, that during the rewinding operation it is highly desirable to eliminate the frictional drive and establish a direct driving connection between the stud 16 and the driving mechanism, so that rewinding may be accomplished in as short a time as possible. This direct drive is especially desirable because the speed of the mechanism is stepped up during the rewinding operation, due to the elimination of the resistance R as heretofore mentioned. In rewinding only the upper reel N is driven. Hence, there is no provision for connecting the lower reel stud 15 directly to its driving mechanism. However, the frictional drive for this stud is the same as for the stud 16.

The driving mechanism for the upper reel is arranged for direct drive during rewinding and is provided with an automatic release which automatically disconnects the direct drive when the mechanism is operated in a forward direction (to wind film on the lower reel W) following the reverse action. This driving connection is best shown in Figs. 10 and 11. The driving stud 16 is supported in a bushing 170 carried by the supporting arm 13 and has loosely mounted thereon the driving gear 130, heretofore mentioned. The gear 130 is disposed between two washers 173 and 174, the first of which is rigidly mounted upon the shaft and the second of which is loosely mounted on the shaft. A spring 175 is then utilized for clamping the gear to the washer, and the tension on the spring is arranged to be adjusted by a set-screw 176. This provides a frictional driving connection between the gear and the reel carrying stud 16. The stud 15

is similarly driven from its respective driving gear 152.

A suitable clutch, shown in Figs. 10 and 11 provides for a direct driving connection between the gear 130 and the reel stud 16. As shown, a sleeve 180 surrounds the inner end of the stud 16 and is acted upon by the spring 175 to make the frictional connection between the stud and the gear, the sleeve being slidably mounted on the stud but prevented from rotation thereon by reason of a flattened end 181 of the shaft engaging a similarly shaped opening in the sleeve. The sleeve 180 carries a pin 182 which engages a slot in a clutch member 183, which slidably embraces the sleeve and is provided with teeth 184 to engage similar teeth 185 formed on the inner face of the gear 130. The clutch member 183 is rotatably mounted in the shank of a hollow plunger 186, relative sliding movement between these two members being prevented by reason of the engagement of a pin 187 carried by the sleeve with an annular groove formed in the clutch member 183. The plunger 186 is in turn slidably mounted in a cap 188, which is secured to the reel arm 13, relative rotation between the cap and the plunger being prevented by a lug 189 on the plunger, which engages a recess in the cap. The outer end of the plunger is provided with a suitable knob, by means of which the plunger may be manually moved to engage the clutch member 183 with the gear 130.

The operation of the clutch is as follows: The operator presses the plunger inwardly toward the stud 16 against the action of a suitable compression spring 190, carrying the clutch member 183 into engagement with the gear 130, thereby providing a direct driving connection between the gear, the clutch member 183, the sleeve 180 and the shaft 16. As the plunger is depressed an ear 194 on the plunger passes an arm 191, carried on a rock shaft 192, and which is normally retained in the position shown in Fig. 11 by a suitable spring 193. As the ear 194 engages the arm it rocks it against the action of the spring 193, and when the ear is past the plunger the spring returns the arm, thereby locking the plunger in its inward or depressed position. As long as the direction of rotation of the parts is in the direction of the arrow on Fig. 11, which direction is the rewinding direction, the plunger will remain depressed.

Upon the first winding movement of the film on the reel W, following the rewinding of the film on the reel N, the plunger 186 is automatically released. The spring 193 which maintains the arm 191 in its normal or locking position, is engaged by the upper end of an arm 195 which is secured to the rock shaft 192. The action of the spring is such as will permit the rocking of the shaft in either a clockwise or counter-clockwise direction. The lower end of the arm 195 projects into a peripheral recess in the hub of the gear 130, and the parts are so arranged that when the gear rotates in the direction shown by the arrow in Fig. 11, the rocking of the shaft 192, due to the arm 195 riding on the periphery of the hub of the gear 130, has no effect on the lock between the plunger 186 and the arm 191. However, when the film is wound on the reel W it is drawn from the reel N, causing the latter to rotate in a direction opposite to the arrow in Fig. 11. The driving connection established through the clutch 183 causes the gear 130 to rotate in the same direction as the stud 16. When this occurs, the arm 195 enters the slot and upon further rota-

tion rides out of the slot onto the periphery of the hub of the gear, swinging the rock shaft into a position to cause the arm 119 to release the plunger, which returns to its withdrawn position 5 under the influence of the spring 190. Hence, the direct driving connection is broken, and when the film is next reversed during the operation of the machine, the film will not be damaged as the frictional driving connection will permit lost motion between the reel and its driving mechanism.

I will now describe the particular embodiment of my control shown in Figs. 2 to 5, inclusive, which effects the above described circuit connections, and which is illustrated, described and 15 claimed in my copending application, heretofore mentioned.

Mounted in the offset portion 18 of the hollow frame is a stationary cup-like housing 20 of insulating material, having a cylindrical wall 21 on 20 a horizontal axis, and a vertical base 22 which has, concentric of the axis, a small inwardly projecting cup portion 23 having a vertical wall 24 at the front. The insulating housing 20 may have a front edge flange 25 overhanging the frame 25 casing 18, to which it may be locked by screws 26.

At the rear of the internal cup portion 23 and bridging across it, is an insulating block 27 secured by screws 28 to the wall 22 and carrying a pair of contacts 31 and 32, which extend 30 forwardly through the block on opposite sides of an opening 29 in the block. These contacts 31 and 32 are L-shaped pieces, as shown, and are secured to the insulating block by screws which clamp to the contact conductors 35 and 36 which 35 are parts of the main current line to the lamp and motor. The inner ends of these L-shaped contacts 31 and 32 are exposed within the cup and are adapted to be bridged by a floating metallic member which coats with them to form the snap 40 switch as previously described.

Rotatively mounted in the annular space within the insulating housing 20 is an insulating barrel 40 integrally carrying an operating knob 41. This barrel has, on its periphery, suitable contacts 45 cooperating with contacts carried by the housing, as hereinafter described. The barrel also carries, rigidly mounted in the knob 41, a rod 50 which has on it a bulging sleeve 51 coming to a central ridge. Surrounding this sleeve is a 50 hollow metallic cage 52 and within this cage is an annular coiled spring 53.

It results from the described construction that if the knob 41 is pulled outwardly, the ridge of the sleeve 51 is moving outwardly, passes through 55 the annular spring 53, and as soon as the ridge has passed that sleeve, the contraction of the spring on the incline of the sleeve causes the cage to snap toward the free end of the rod 50, thus making a contact with the terminals 31 and 60 32, as shown in Fig. 3. On the other hand, when the outwardly drawn knob is pushed inwardly, the rear conical portion of the sleeve 51 passes through the spring of the cage, expanding the spring, and, as the ridge passes beyond the spring, 65 the contracting spring causes the bridging cage to snap out of contact with the terminals 31 and 32 and come into the position at the head of the cup 23 as shown in Fig. 2.

The rotation of the knob 41 establishes the various electric circuits as desired, and then the outward pulling of the knob closes the switch to 70 make these circuits effective, and when the knob has been so pulled, it is locked against rotation, so that the circuit cannot be disturbed until the 75 knob has been pushed inwardly and broken the

circuit. To enable this control of the knob, I form in the periphery of the barrel 40, an annular groove 44 which is occupied by the inner end of a pin 45 mounted in the wall 21 of the insulating housing 20. The barrel, when in idle position, as 5 shown in Fig. 2, may be rotated freely, the groove 44 traveling across the pin. At each of the active positions of the knob, however, I form a longitudinal offset 46 of the groove 44, as indicated in Figs. 2 and 5. When one of these offsets is in 10 registration with the pin, the knob may be pulled outwardly into the position shown in Fig. 3, and when so pulled, the pin occupying the corresponding offset, prevents the rotation of the knob.

For convenience of illustration, I have shown 15 the pin 45 in the plane of the sections of Figs. 2 and 3. However, in practice it is inconvenient to locate the pin in this particular location as the contacts in the periphery of the barrel interfere with the offsets 46. The preferred location of the pin is as illustrated at 45 in Fig. 4. It could have any location about the periphery of the barrel if the barrel were long enough so that the offsets 46 could not interfere with the contacts on the periphery of the barrel, but to 25 condense the construction I prefer to make the barrel quite short and arrange the offsets to lie between the peripheral contacts.

The contacts on the barrel above referred to are simply plates mounted in the periphery 30 adapted to bridge two stationary contacts carried by the housing. In Figs. 2 and 3 I illustrate at 60 one of the housing contacts which is connected at its rear to a conductor 76, and these views illustrate at 80 one of the bridging contacts 35 mounted in the barrel, these bridging contacts being short metal plates having arcuate exteriors and mounted in notches in the periphery of the barrel. The plates may be backed up by springs 82 pressing them outwardly.

In the particular embodiment shown, there are 40 seven of these peripheral plates mounted on the barrel and designated in Fig. 4 as 80 to 86, inclusive. In the housing 20 there are in this embodiment eleven contacts similar to 60 designated from 60 to 70, inclusive. I have given the contacts each a different designating number 45 in Fig. 4 for the purpose of identification with the diagrams of Figs. 12 to 15. These contacts have been arranged after much experimenting, 50 to give the various connections desired for the four active positions of the knob and without causing any disturbances of these connections by the non-active contacts.

The active positions of the barrel are preferably on somewhat less than half of its face, as 55 illustrated in Fig. 1. The barrel when idle may stand in any position, but it is shown in Fig. 1 in the position of being ready for forward running; then a simple outward pull of the knob 60 illuminates the lamp and energizes the motor, driving the lower roll and intermittent feed and the shutter, thus projecting the picture. When the knob is pushed inwardly, the current is cut off to all parts, then it may be rotated to any 65 of the other three positions and the film projected backwardly, if desired, or wound rapidly and directly from the reel W onto the reel N, or left in any standing position subject to the control of the hand knob 170.

I will now describe the circuits for the four 70 positions, as indicated by the four diagrams Figs. 12 to 15.

In Fig. 12, which indicates the forward drive, the current comes from a suitable source of sup- 75

ply indicated at 100, thence through the resistance R and the line 101 to the field F of the motor, through that field to the line 102, back through the closed switch 103 (that is the switch 5 31, 32 and 52 of Fig. 2) to the minus line 104 to the source of supply, indicated conventionally by the battery though it will usually be an ordinary 110 volt lighting circuit. The switch 103, however, will be open until the knob has been 10 pulled longitudinally.

The line 101 at a point where it joins the field F also continues as 105 to the fixed contact 70. This contact in this position is connected by the bridging contact 86 on the rotary barrel to the 15 contact 69 which is connected by the line 106 with the armature M of the motor. On the other side of this armature the line 107 leads to the contact 63 in the housing. This is connected by the bridge 83 to the contact 64, from which a 20 line 108 leads to the line 102 on the negative side of the field. The armature is thus in a shunt across the field. The line 109 branches from the line 102 and passes through the lamp L to the contact 65 which is engaged by the 25 bridge 84 and connected with the contact 66, from which a line 110 leads back to the plus side of the source of supply. The lamp and motor are thus in parallel with each other on two 30 branches of a divided circuit. When the parts 35 are in this position, the solenoid S is idle, the lamp and motor are energized, and the direction of drive is forward.

In Fig. 13 the connections are the same as Fig. 12, except that the motor armature has been 40 reversed with reference to the field; that is to say, the line 106 from the armature M to the contact 69 is now connected by the bridge 80 with the contact 68, from which a line 111 (which was idle in Fig. 12) leads to the line 102 connected to the negative side of the field F. The line 107 from the other side of the armature which terminates at the contact 63 is now connected by the bridge 84 with the formerly idle contact 62, from which a line 112 leads to the 45 main line 101 on the plus side of the source of supply.

The connections for rewinding (Fig. 14) leave the motor, field and armature coupled as in reverse, but the resistance and the lamp are out of circuit. On the other hand, the solenoid S is in circuit, the line 113, 114 from the main line 103 through the solenoid and terminating at the contact 61 being connected by the bridge 82 to the formerly idle contact 60, from which a line 115 leads to the line 110 going back to the plus side of the source of power. The solenoid is thus bridged across the main lines and is active to disconnect the drive to the lower reel W and disconnect the intermittent feed and shutter.

In Fig. 15 (for still exhibition) the connections are similar to Fig. 14, except that the lamp and resistance are now again energized and while the motor is reversed; the solenoid being energized, the drive to the lower reel W is cut out and the motor drive to the reel N is non-effective (turning in the backward direction) so that in this case the motor is used simply to operate the fan for cooling the lamp. The line 105 from the plus side of the field becomes active in this last connection and leads to the contact 70, which is connected by the bridge 82 with the contact 69, which leads via the line 106 to the armature, and from the other side of the 75 armature the line 107 leads to the contact 63 and

is connected by the bridge 86 with the contact 64 from which the line 108 leads to the minus side of the field, the motor being thus connected as in Fig. 1.

It will be seen from the tracing of the diagrams, 5 that a bridging contact on the periphery of the rotary barrel is adapted to serve in several locations for bridging different contacts of the stationary housing, and at the same time these contacts are so arranged that there is no interference of one with the other. For instance, the contact 86, which in Fig. 12 bridges the contact 69 and 70, is idle in Fig. 13, in Fig. 14 bridges the contacts 66 and 67, and in Fig. 15 contacts 63 and 64.

It will be seen, from the description given, that I have provided a very compact mechanism in association with a unitary electric control, enabling the machine to perform the four operations of ordinary exhibiting, reverse exhibiting, still exhibiting, and re-winding, each by a single setting of the control device. The whole mechanism is very compact and experience has demonstrated that it is steady and comparatively noiseless in operation.

The motor-operated mechanism is so arranged that it becomes automatically disconnected from the supply reel whenever the movement is in a direction to drive the take-up reel. I attain simplicity and compactness of parts by arranging the intermediate driving member for the take-up reel, the driving member for the intermittent feed, and shutter all on one shaft, which is normally driven by the motor. On the other hand, I drive the supply reel in a very simple 30 and direct manner by means of a mechanism which comes into action automatically upon the reverse movement of the motor, and a clutch which entirely disconnects the intermediate shaft and the parts it carries, so that no extra work 35 is thrown on the motor during the re-winding operation, and this permits the motor to assume its maximum speed during the re-winding. Furthermore, for this rewinding I provide a manual clutch to make a positive connection between 40 the re-winding reel stud and the driving mechanism to avoid any loss from slippage during 45 this high-speed action.

Finally, to prevent the positive connection at the re-wind stud from resulting in any subsequent damage to the film, if the operator were 50 required to disengage it and neglected to do so, I provide automatic mechanism which establishes the disconnection immediately upon the reversal of movement of the reel, irrespective of any mechanical driving connection to that reel.

I claim:

1. In a motion picture projector, a pair of film reels, driving mechanism therefor, including a reversible electric motor, a frictional driving connection disposed between one of said reels and the motor, means to cause said connection to be replaced by a direct driving connection, and means acting automatically consequent upon the reversing of the direction of rotation of said motor for causing said first-named means to disengage the direct driving connection between the motor and the reel.

2. In a motion picture projector having a pair of film carrying reels, mechanism to alternately 70 drive said reels to wind film on the driven reel from the other reel, including an electric motor and clutch mechanism connecting said motor to selectively drive either of said reels, as desired, a frictional driving connection disposed between 75

one of said reels and the motor, a positive drive connection connecting said last-named reel with said motor, and means responsive to film pull irrespective of any other driving connection to 5 said last-named reel to release said positive driving connection.

3. In a motion picture projector having a film carrying reel, a motor, a driving connection between said motor and said reel, a frictional power transmitting unit connecting said motor with said reel, a clutch mechanism to selectively cause said reel to be positively connected with said motor, a manually operable plunger for controlling said clutch, and a catch coacting with 15 said clutch to retain the clutch in an operating position.

4. In a motion picture mechanism having a film carrying reel rotatably mounted thereon, operating mechanism to rotate said reel, said 20 operating mechanism including a frictional driving connection, resilient means to maintain said frictional driving connection, a clutch for positively connecting said reel with said operating mechanism, said clutch including a member fixed 25 to rotate positively under the influence of the operating mechanism and a member fixed to rotate positively with said reel, one of said members being movable to engage the other member and cause both of said members to rotate positively as a unit, means to normally keep said 30 members disengaged, a manually operable plunger for engaging said members, a catch responsive to the direction of rotation of one of said members for maintaining said members in driving engagement with each other when the member is rotating in one direction and for releasing said members from engagement with each other when the member is rotating in the opposite direction.

5. A motion picture projector comprising 35 studs for carrying a pair of film reels and mechanism for driving the same, an intermittent movement mechanism to progress said film from one reel to the other, and a shutter, a reversible 40 motor for operating the reels, intermittent movement and shutter, together with a solenoid-controlled clutch for disconnecting the intermittent movement and shutter, a unitary control device which may be set in alternative positions and 45 having contacts which in one position energize the motor in the direction to drive one reel, and in another position act to reverse the direction of the motor and thereby drive the other reel, said contacts in another position actuating the 50 solenoid to enable exhibition of a still picture.

6. In a motion picture projector, having two film reels adapted to carry film, a pair of ratchet devices for driving the two reels, an intermittent feed mechanism, including a clutch to carry 55 said film from one reel to the other, a lamp, a fan therefor, and a motor for operating the fan, the intermittent feed and the two ratchet reel drives; a resistance for controlling the motor speed; and a solenoid for unclutching the intermittent feed, combined with, and controlled by, a unitary control device having the following 60 positions, namely: one position for operating the motor through the resistance to drive the fan, the intermittent feed and one reel; a second position for operating through the resistance the motor in the reverse direction to drive the fan, the intermittent feed reversely, and the other reel; a third position for operating the motor 65 without the resistance and with the intermittent

feed unclutched whereby the motor may operate rapidly to rewind the film; a fourth position to energize the motor to operate the fan to cool the lamp without operating the intermittent feed or either reel, whereby a still picture may be exhibited. 5

7. In a motion picture projector having two reels adapted to carry film, a pair of ratchet devices for driving the two reels, a shutter, an intermittent feed mechanism, to feed said film 10 from one reel to the other, a lamp, a fan therefor, a motor for operating the fan, the intermittent feed and the two ratchet reel drives, a solenoid for disconnecting the intermittent feed, the shutter and one of said ratchet drives from 15 said motor combined with, and controlled by, a unitary control device having the following positions, namely: one position for operating the motor to drive the fan, the intermittent feed and one reel; a second position for operating the 20 motor in the reverse direction to drive the fan, the intermittent feed reversely and the other reel; a third position for operating the motor with the intermittent feed unclutched, whereby the motor may operate rapidly to 25 rewind the film; a fourth position to energize the motor to operate the fan to cool the lamp without operating the intermittent feed or either reel, whereby a still picture may be exhibited.

8. In a motion picture projector, a pair of 30 film reels, an intermittent film feed mechanism, a shutter, a lamp, a fan therefor, a continuous film feed, a reversible motor for driving said fan, said pair of reels, the intermittent feed, the shutter, and the continuous film feed, a clutch 35 for disconnecting the continuous feed, the intermittent feed, the shutter and one of said reels from said motor to render them inoperative with respect thereto, and a second clutch responsive to the direction of rotation of said 40 motor to disconnect the other one of said pair of reels from rotation induced by said motor.

9. In a motion picture projector, a pair of film reels, an intermittent film feed mechanism, a shutter, a lamp, a fan therefor, a continuous 45 film feed, a reversible motor for driving said fan, said pair of reels, the intermittent feed, the shutter, the film feed, and the continuous film feed, a clutch for disconnecting the continuous feed, the intermittent feed, the shutter and one 50 of said reels from movement resulting from said motor, and a second clutch responsive to the direction of rotation of said motor to disconnect the other one of said pair of reels from rotation induced by said motor, and a unitary control 55 device to control the supply of power to said motor, the direction of rotation of said motor and said first-named clutch.

10. In a motion picture projector, using film and having a pair of reels, an intermittent film 60 feed mechanism, a shutter, a lamp, a fan therefor, a continuous film feed, a reversible motor having a vertically disposed armature shaft, a connection between said shaft and one of said reels, including a clutch responsive to the direction of rotation of said motor to connect or disconnect the shaft with said reel, a horizontally disposed shaft drivingly connected to said armature shaft through the medium of a solenoid 65 controlled clutch, said horizontal shaft arranged to drive the shutter, the intermittent feed and the continuous feed, said horizontal shaft also connected to drive the other of said reels, said last-named connection including a clutch responsive to the direction of rotation of the motor 70

to disconnect or connect the horizontal shaft with said last-named reel.

11. In a motion picture projector having a pair of film reels, an intermittent feed mechanism for said film, a shutter, a lamp, and a fan therefor, a continuous film feed, a reversible motor having a vertically disposed armature shaft, a connection between said shaft and one of said reels, including a clutch responsive to the direction of rotation of said motor to connect or disconnect the shaft with said reel, a horizontally disposed shaft drivingly connected to said armature shaft through the medium of a solenoid controlled clutch, said horizontal shaft being arranged to drive the shutter, the intermittent feed and the continuous feed, said horizontal shaft also being permissive of connection to drive the other of said reels, said last-named connection including a clutch responsive to the direction of rotation of the motor to disconnect or connect the horizontal shaft with said last-named reel, and a unitary control device manually operable at the will of the operator to energize said motor with or without energizing the solenoid and to control the direction of rotation of said motor.

12. In combination, a motion picture projector employing a strip of film, mechanism for driving the film in either one of two directions, a motor to operate said mechanism, a plurality of electrical circuits to control said motor, and a settable control device having one movement for selectively controlling the direction of feed of said film by selecting the appropriate electrical circuit to operate said motor in a desired manner, together with a second settable movement adapted to connect and retain connection or disconnect and retain disconnection of the chosen one of said circuits with a source of current supply.

13. A motion picture projector having means for carrying a pair of reels, a roll of film adapted to be fed from one reel to the other, a driving motor and suitable mechanism for causing the machine to feed the film from either reel to the other or to cease feeding the film to exhibit a still picture, a mechanical clutch disposed between said motor and said mechanism, a plurality of electrical operating circuits to control the direction of rotation of said motor, and a manually operable settable control device for selectively engaging one of said electrical circuits to cause a given operation, as desired by the operator, said control device being slidable to control a single circuit supplying current to the chosen one of said operating circuits, means to retain said slidable device in either an active or inactive position, as desired, and a solenoid to actuate said clutch and controlled by said device.

14. A motion picture projector comprising a stud for carrying a pair of film reels, mechanism for driving the same, an intermittent movement mechanism to progress said film from one reel to the other, a shutter, a reversible motor for operating the reel, intermittent movement and shutter, a solenoid together with a clutch controlled by said solenoid for disconnecting the intermittent movement and shutter as desired, a unitary manual control for said mechanism to control said solenoid, and means whereby films may be rapidly rewound from one reel to the other while said intermittent movement and shutter are retained inactive.

15. In a motion picture projector, a film reel, means to drive said film reel, a frictional connection between said driving means and said reel

and means to effect a positive driving connection, together with means to disengage said positive driving connection when the direction of rotation of said reel is reversed.

16. In a motion picture projector, a pair of film reels, reversible driving mechanism therefor, including a reversible motor, a frictional driving connection disposed between one of said reels and the driving mechanism therefor, means to cause said connection to be replaced by a direct driving connection, and means acting consequent upon the reversing of the direction of rotation of said motor for causing said direct driving connection between the driving mechanism and the reel to be disengaged when the direction of rotation of said reel is reversed.

17. In a motion picture projector, a film-carrying reel, driving mechanism therefor, a driving connection between said mechanism and said reel, a frictional power-transmitting unit connecting said mechanism with said reel, a clutch mechanism to selectively cause said reel to be positively connected with said driving mechanism, manually operable means for controlling said clutch and means to disengage said clutch when the direction of rotation of said reel is reversed.

18. In a motion picture projector employing a strip of film carried by a pair of reels, electrically operated mechanism for driving the film from either reel to the other, as desired, an intermittent feed to move said film in one direction, and a single manual settable control device for the mechanism, said control having a dual operation, one of said operations being adapted to selectively effect the movement of said film in either direction, as desired by the operator, and means embodied in said control to permit a second settable operation, perpendicular to said first operation for supplying power to cause the chosen film movement to be effective and a mechanical clutch, electrically governed by said control, to maintain or discontinue said intermittent feed depending on the setting of said control.

19. The combination of a motion picture projector adapted to be operated in various ways, mechanism embodied in such projector to permit such various operations, including an intermittent feed for said film, a single control switch rotatable into different positions to select a given manner of operation, said control having means to permit a second movement perpendicular to said first movement and settable in a chosen position to initiate the selected operation and render said rotative selection operationally effective, a mechanical clutch to control said intermittent feed and means to control said clutch by means of said control switch.

20. The combination with a motion picture projector adapted to be operated in a plurality of alternate ways, one way embodying an intermittent feed for a film of a unitary control device to permit said projector to operate in the chosen one of said alternate ways, said control device having means to permit movement in one direction to select an operation to be performed, and means to permit movement in a direction normal to said first movement to initiate the selected operation chosen by said first movement, both of said means being settable to be retained in a chosen position, said control including means whereby such selection is rendered effective in operating said projector and a mechanical clutch, electrically controlled by said switch for controlling said intermittent feed.

21. The combination of a motion picture projector, conduits within said projector creating a plurality of electrical circuits, a unitary control for said circuits, contacts on said control to engage a control arm which is rotatable to select the operation to be performed, a member in said control having a longitudinal movement to initiate the selected operation, and means to retain said control at either extreme of said longitudinal movement as desired, and a mechanical clutch which is electrically controlled by said switch to govern the operations to be performed.
22. The combination with a motion picture projector, of mechanism for operating said projector to pass film therethrough in either of two opposite directions, including means to drive the advance reel when projecting or to retain said film in a stationary position, electrically operated means for causing said different operating movements, including a mechanical clutch for connecting said advance reel to a driving source, conduit wires forming a plurality of electric circuits to control said electrically operated means, a unitary control for said circuits comprising a rotary barrel, peripheral contacts on said barrel adapted to coact with an adjacent set of fixed contacts on said control to establish the electrical circuit desired, said barrel being movable longitudinally and settable in either an active or inactive position to close a main circuit energizing the chosen of the alternative circuits. 10
